UNITED STATES PATENT OFFICE.

BENNO SCHUBART, OF NUERMBERG, GERMANY, ASSIGNOR TO VEREINIGTE SCHUHFABRIKEN BEMEIS-WESSELS AKTIENGESELLSCHAFT, OF AUGSBURG, OBERHAUSEN, GERMANY.

DESIGN FOR A BABY'S SHOE.

Application filed July 21, 1928, Serial No. 27,557, and in Great Britain March 29, 1928. Term of patent 3½ years.

To all whom it may concern:

Be it known that I, BENNO SCHUBART, a citizen of the German Republic, residing at Nuremberg, Germany, have invented a new, original, and ornamental Design for a Baby's Shoe, of which the following is a specification, reference being had to the accompanying drawing, forming part thereof.

The figure is a front perspective view of a baby's shoe showing my new design.

I claim:

The ornamental design for a baby's shoe as shown.

BENNO SCHUBART.
